WILLIAM STEMBELL STORMS, OF MIDDLETOWN, OHIO.

Letters Patent No. 63,670, dated April 9, 1867.

FURNACE FOR STEAM BOILERS.

The Schedule referred to in these Letters Patent and making part of the same.

TO WHOM IT MAY CONCERN:

Be it known that I, WILLIAM STEMBELL STORMS, of Middletown, in the county of Butler, and State of Ohio, have invented certain new and useful improvements in Smoke-Consuming Furnaces; and I hereby declare the following to be a full, clear, and exact description of the same, reference being had to the accompanying drawings, in which—

Figure 1 is a transverse section of a furnace constructed in accordance with my invention, used in connection with an ordinary steam boiler.

Figure 2 is a horizontal section of the same; and

Figure 3 is a longitudinal vertical section.

The primary object I have in view in my invention is to consume the smoke and other products of combustion evolved by the burning fuel in a furnace, and to employ the heat and flame generated by the combustion of these products, so as to intensify to a high degree the heat to which the boiler or other object to be heated is exposed.

When the ordinary method of burning fuel is employed, there result a great loss and waste of fuel. The smoke and other products of combustion evolved from the fuel, instead of being used as just indicated, are ordinarily conducted off and discharged from the fire-chamber as fast as they are generated. These products of combustion consist, however, for the most part of gases (hydrocarbon) of a highly combustible nature, which are not consumed in the fire-chamber only for the reason that the supply of oxygen to the furnace is not sufficient to effect the complete combustion of the fuel. The gases are, in fact, fuel in a light and highly divided state, already heated and prepared for immediate and complete combustion, which takes place as soon as they are brought in contact and intermingled with the requisite supply of oxygen. An intensely heated flame is thus produced, which can be directed upon the object to be heated so as to increase by many degrees the heat evolved from the fuel. It becomes, therefore, a great desideratum to devise means by which this supply of gaseous fuel may be saved and utilized, and, as above said, the primary object of my improvements is to effect this result. To this end my invention principally consists in the method of first collecting the products of combustion in a chamber apart from the fire-box of the furnace, then effecting their combustion by intermingling them with heated atmospheric air, and then directing the heat and flame thus evolved back into the fire-chamber, causing them to impinge at the same time against the surface of the object to be heated, and to intensify the heat already evolved from the fuel.

In order to effect a thorough and rapid mingling of the oxygen with the products of combustion, I arrange the fire-chamber flues, one on each side of the atmospheric air flue, so that the air when issuing from its flue may immediately unite with the gases which are being discharged from the flues leading from the fire-chamber. The chamber or chambers in which the products of combustion are thus ignited may be formed in any suitable manner, the only requisite being that it should have flues which communicate as above described with the fire-box and with the outside air, and that it should also be provided with another passage or opening through which the products of combustion, when oxygenated and inflamed, may return to the fire-chamber. In the drawings, in which my invention is illustrated as applied to an ordinary steam boiler, these are chambers, A, formed above and on each side of the fire-chamber F, by means of the upper arch B and the lower arch or fire-bridge C, which directs the heat of the fuel upon the boiler. The spaces enclosed between the two arches and the sides of the boiler constitute these chambers. Each one of them communicates with the fire-chamber by means of flues, a, which are formed in the fire-walls and bridge C, on each side of the atmospheric air flues b. These latter extend to the outside of the furnace, and, of course, communicate with the surrounding air. The boiler itself at each end rests upon the solid masonry of which the front and back walls of the furnace or fire-chamber are formed. The upper arch B, which nearly covers the upper part of the boiler, is closely in contact therewith. The lower arch or fire-bridge C, on the contrary, does not come in contact with the boiler, but there is left a space, e, between the two, for the purposes hereinafter mentioned. The auxiliary chambers on each side of the fire-box are thus hermetically tight on top, their only means of communication with the outside air being through the air flues b. In the back wall of the fire-chamber, just underneath the boiler, a flue, d, is formed, through which the cinders and residuum of incombustible gases, if there be any, pass. The cinders drop through the opening E, formed in the bottom of the furnace, and the gases are carried off through the chimney.

The operation of the furnace is as follows: The fuel, either coal or wood, is supplied to the fire-chamber through the fire-door of the furnace. As soon as it begins to burn it evolves smoke and other gaseous products of combustion in a highly heated state; these gases rise, and, leaving the chamber, ascend through the flues *a*, formed in the fire-walls and bridge *C*, into the chambers *A* on each side of the boilers. Immediately upon being discharged from the flues they become oxygenated by contact with the air, which during its passage through its flues, *b*, has become also greatly heated, and the union of the two produces an intense heat and flame, which being driven forward strikes the curved top of the chamber, by which they are deflected so as to be brought against the surface of the boiler. They thus impinge against a considerable portion of the boiler, along the surface of which they pass through the space *c* left between it and the lower arch or fire-bridge *C*, until they again return to the fire-chamber *F*, where they mingle with and intensify the heat already there. The residuum of gases and the cinders thence pass out through the flue *c* in the back wall of the fire-chamber into the space beyond, where the cinders drop to the ground, and the unconsumed gaseous products of combustion (if there be any) are carried off through the chimney.

It will be perceived that the method I have just indicated, while it enables us to effect the complete consumption or combustion of all the gases evolved by the burning fuel, possesses also other important advantages. The boiler does not bear upon or come at all in contact with the fire-bridge *C*, but is held and supported entirely by the masonry which forms the front and back of the fire-box. The arch is by this means unsubjected to any strain or pressure which might injuriously affect it, and there is but little liability of its getting out of repair. The arrangement of the air and fire-chamber flues is such, also, that the air is projected into the midst of the gases, which are thus thoroughly and immediately intermingled with the oxygen.

It will of course be understood that my improvements, subject to modifications which will readily suggest themselves, can be employed in many connections, and applied to all species of boilers, or used for heating purposes in general.

Having described my invention, what I claim, and desire to secure by Letters Patent, is—

1. The combination, with the fire-chamber of a furnace or other heater, of an auxiliary chamber communicating with the fire-chamber and outside air through flues and passages arranged substantially as shown and described;
2. The combination of the fire-chamber and boiler with the upper arch and lower arch or fire-bridge of the furnace, under the arrangement and for operation as shown and described.

In testimony whereof I have signed my name to this specification before two subscribing witnesses.

WILLIAM S. STORMS.
